7531X Joseph Roy

April 12, 1833

Letters Patent.

The Schedule referred to in these Letters Patent, and making part of the same, containing a description in the words of the said Joseph Roy, himself, of his improvement, in the machine for shelling corn.

To all whom it may concern. Be it known that I, Joseph Roy, of Bannbrook, Somerset County, New-Brig, have made an improvement in the machine for shelling corn, which is described as follows. - This machine, consists of the following principle parts, viz. The frame which supports and contains the machinery, the two frustums of cones, covered with pins or projections; the concave beds, covered with sheet iron, in which the cones work; the springs for pressing the beds towards the cones; and the gearing by which the machinery is turned. The frame is constructed, by mortising and tenoning together four posts, two side pieces, two end pieces, and a frame around the top, so as to produce a square, or parallelogram figure, of sufficient size, to receive the several parts of the machinery. The two frustums of cones are placed with their apices, joined in the center, and they are covered all over with pins or projections, at a proper distance apart for rubbing out the corn; they turn on an axle, supported in boxes in the frame. This axle is prolonged to receive a wheel, and any wheel whatever after described. These frustums of cones may be made of wood and covered with cast iron plates, having projections on them instead of pins, described in a before described; or it may be cast wholly of iron and projections or teeth, on its outer surface. A concave bed is placed against each cone of the same elevation as the cone, and calculated to admit of its turning freely in it. Two or more springs, are placed behind each bed, which press it against the cone. The support of these concave beds, consists of two broad pieces of timber, placed in a sloping position from the center of the machine, having

having a number of openings through them, to admit the grains of corn to fall through; which pieces of timber with the concave base are brought nearer, or farther from the cones by screw bolts, passing through them ends, and the side pieces of the frame. The gearing for turning the machinery, is a small cogwheel, and a wheel, placed on the same axle, with the cones. This cogwheel works into another cogwheel, placed on the axle of the driving power; another which is placed on an axle, at the hinder end of the frame, for turning a fanning mill;— a band passes round this wheel and that, upon the axle of the double cone. A hopper is placed in the centre, and above the double cone, for receiving the ears of corn. A inclined board, is placed below the double cone, and beds, to receive the corn as it is shelled, and to conduct it to the end of the machine, where the fan is placed. The winnowing machine, is made, and acts in the usual manner— Operation.— The hopper being filled, and the machine put in motion by any convenient power, the ears descended between the cones, and beds where the grains are rubbed off, by the projections or pins, the grain, descending down the inclined plane, to the winnowing machine, and the chaff flying out at the sides of the machine. The invention, here claimed, and desired to be secured by Patent, consists, of the combination and arrangement of the several parts of the before described machine for shelling corn; but particularly the two fixtures of beds, united in the centre, and covered with teeth, or projections, to claim is made to the other parts of the machine taken separately.— For a further illustration of my invention, I refer to the model and drawing of the same deposited in the Patent Office. In testifying whereof, I hereunto subscribe my name, this 6th day of April 1838.

Witness,

En'td. J. William & Collector
Atto. Thomas A. Collector

Joseph Rose.

(Signed April 6th 1838.)
